CLAIM

The ornamental design for a display screen with graphical user interface for editing and running project as shown and described.

DESCRIPTION

FIG. 1 is a front view of a first image of a display screen with graphical user interface for editing and running project showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is a front view of a fourteenth image thereof;

FIG. 15 is a front view of a fifteenth image thereof;

FIG. 16 is a front view of a sixteenth image thereof;

FIG. 17 is a front view of a seventeenth image thereof; and,

FIG. 18 is a front view of an eighteenth image thereof.

The broken lines consisting of evenly spaced dash lines in the drawings depict portions of the display screen with graphical user interface for editing and running project that form no part of the claimed design.

The appearance of the images sequentially transitions between the images shown in FIGS. 1-18. The process or period in which one image transitions to another image forms no part of the claimed design.
